OF BELLEVUE, WASHINGTON.

ADJUSTABLE CLOTHES-RACK.

1,191,312.

Specification of Letters Patent. Patented July 18, 1916.

Application filed August 23, 1915. Serial No. 46,765.

To all whom it may concern:

Be it known that I, NELS JENSEN, citizen of the United States, residing at Bellevue, in the county of King and State of Washington, have invented a certain new and useful Improvement in Adjustable Clothes-Racks, of which the following is a specification.

My invention relates to improvements in adjustable clothes racks, and the object of my improvement is to provide a clothes rack which shall embody a plurality of hanger arms all hinged to a vertically disposed pivot-rod in such manner that each of them shall be adapted to be moved independently to swing from the same vertical plane to any desired point in a horizontal plane, said pivot-rod being mounted on a carrier that may be slidably moved to and fastened at, any desired point on a vertically disposed shaft which is rotatable in suitably supported bearings, whereby said hanger arms may be quickly placed at a convenient height for hanging clothes thereon and then raised to and be sustained at a desired height with each disposed at a desired angle with respect to the others. I accomplish this object by devices illustrated in the accompanying drawings wherein—

Figure 1 is a view in front elevation of a clothes rack embodying my invention; Fig. 2 is a plan view of a detail of the same; Fig. 3 is a view in cross-construction on broken line x, x of Fig. 1; Fig. 4 is a fragmentary view in front elevation of a clothes rack embodying a modified form of operative parts of my invention; and Fig. 5 is a view in cross-section of the same on broken line y, y of Fig. 4.

Referring to the drawings, throughout which like reference numerals indicate like parts, 6 is a supporting standard, preferably of wood, which may be fastened in a vertical position against the wall of a room or against a post, upon the front of the upper end portion of which standard is securely fastened a bracket 7 which is provided with a square hole 8 and a smaller round pivot hole 9 extending vertically downward through it. Within the square hole 8 is a pulley 10 that is mounted freely to rotate on a fixed pivot-rod 11 disposed with its axis at right angles with the plane of the standard 6, as more clearly shown in Fig. 2.

On the front of the lower end portion of

the standard 6 is secured a bracket 12 which is provided with a pivot hole 13 (indicated by dotted lines) which pivot hole 13 is disposed with its axis in the same vertical line with the pivot hole 9 of the bracket 7 and within said pivot holes 9 and 13 are disposed the pivots of a rotatable shaft 14 of rectangular cross-section which extends vertically between the brackets 7 and 12.

A carrier 15 is provided with two rearwardly projecting lugs 16 and 17 by which said carrier 15 is mounted on the shaft 14 in such manner that it may be freely moved vertically to any position thereon, said lugs 16 and 17 being bifurcated and disposed each with one member of its bifurcated portion slidably engaged with a different side of said shaft 14 and between the outer end portion of the members of the bifurcated portion of the lug 16 is pivotally mounted a rotatable roller 20 which engages with one side edge of the shaft 14 while between the inner end portions of the members of the bifurcated portion of the lug 17 is another roller 21 similarly mounted to engage with the opposite side edge of said shaft 14, said rollers 20 and 21 being indicated by dotted lines in Fig. 1. The carrier 15 is also provided with forwardly projecting lugs 18 and 19 within which is fixed a pivot-rod 35 that extends vertically therebetween, which pivot-rod 35 serves as a pivot upon which is mounted a plurality of hanger arms 22 each of which is thus adapted independently to be moved to swing in a horizontal plane to any desired angle with respect to any one of the others thereof and with respect to the vertical plane of the carrier 15, as indicated in Fig. 3. When the hanger arms 22 are in disuse they may be all disposed in the same vertical plane with the plane of the carrier 15, as shown in Fig. 1, and there be confined by the two members of a bifurcated arm 23, which two members are adapted to straddle and engage with the sides of the hanger arms 22, said bifurcated arm 23 being pivotally attached to a bracket 24 to be movable in a vertical plane, which bracket 24 is fastened to the top surface of the carrier 15 as shown in Figs. 1 and 3.

The relative positions of the rollers 20 and 21 with respect to the side edges of the shaft 14 and with respect to the hanger arms 22 are such as will cause said hanger arms always to be disposed in horizontal

planes irrespective of changes in the vertical position of said carrier 15, which carrier 15 may be raised and lowered by a cord 25 to any desired position on the shaft 14 that may be most convenient for utilizing the hanger arms 22; said cord 25 having one of its ends attached to a screw eye 26 fixed in one member of the bifurcated lug 16 to extend upwardly and over the pulley 10 thence 10 downwardly to a cleat 27 to which said cord 25 may be fastened to maintain the hanger arms at a desired height. Thus the carrier 15 may be placed at a desired height and be swung with the shaft 14 to any desired angular position with respect to the plane of the supporting standard 6.

In Figs. 4 and 5 I have illustrated a structure like the structure of Figs. 1, 2 and 3 together with additional mechanism comprising a toothed rack 28 and a weighted arm 30 that is provided with an integrally attached dog 29. The toothed rack 28 is secured to one side of a shaft 31 (which corresponds to the shaft 14 of Fig. 1) and 25 the weighted arm 30 is pivotally attached to the bottom surface of a carrier 32 (which corresponds to the carrier 15 of Figs. 1 and 3) so that said dog 29 is adapted to engage with the teeth of the toothed rack 28 to support the carrier 32 with its associated load at a desired point on the shaft 31. A cord 33 (which corresponds to the cord 25 of Fig. 1) is attached to the weighted arm 30, instead of being attached to a lug on the 30 top portion of the carrier 32, and said cord 33 may be pulled to disengage the dog 29 from the teeth of the toothed rack 28 and to raise the carrier 32 to a desired point on the shaft 31, and when said cord is abruptly 35 released the weight of the weighted arm 30 will cause said dog 29 again to engage with the adjacent one of teeth of said toothed rack 28 thus to lock the carrier 32 at the desired point on the shaft 31; if, however, the 40 free end of the cord 33 be manipulated to allow the carrier 32 to move slowly downward then the dog 29 will be maintained in a disengaged relation to the teeth of the toothed rack 28, thus to permit said carrier 45 to be lowered to a desired point on said 50

shaft 31 whereupon said cord 33 may be abruptly released to cause the weighted arm 30 to move the dog 29 into engagement with the adjacent one of the teeth of the toothed rack 28 in an obvious manner to lock the 55 carrier 32 at said desired point on said shaft 31.

The operation of the structure of Figs. 4 and 5 does not require a cleat corresponding to the cleat 27 of Fig. 1 since the free 60 end of the cord 33 need not be secured to a cleat.

Manifestly, changes may be made in the forms, dimensions and arrangement of parts of my invention without departing from the 65 spirit thereof.

What I claim is:

In a clothes-rack of the class described, the combination with a supporting standard provided with two brackets disposed to project outwardly one from the top end portion and the other from the bottom end portion thereof, of a shaft disposed vertically to be rotatable in bearings formed in said two brackets; a toothed rack secured to said 75 shaft in a position lengthwise thereof; a carrier slidably mounted on said shaft and adapted to be moved vertically to different points thereon; a weighted lever arm provided with an integral dog and pivotally 80 attached to the bottom portion of said carrier in such position that said dog may be engaged and disengaged with a desired one of the teeth of said toothed rack; and a cord having one of its ends attached to said 85 weighted lever arm to extend upwardly therefrom to adapt it to operate to actuate said weighted lever arm to cause its dog to engage and disengage with an adjacent one of the teeth of said toothed rack whereby 90 said carrier may be raised and lowered on said shaft to a desired point thereon and securely maintained at such point.

In witness whereof, I, hereunto subscribe my name this 10th day of August A. D., 95 1915.

NELS JENSEN.

Witnesses:

FRANK WARREN,
A. HASKINS.
